UNITED STATES PATENT OFFICE.

OLNEY W. HOWLAND, OF LYNN, MASSACHUSETTS, ASSIGNOR TO HENRY E. PRIDMORE, OF CHICAGO, ILLINOIS, A CORPORATION OF ILLINOIS.

REST FOR MOLDING-MACHINE FLASKS.

Application filed July 29, 1918. Serial No. 247,143.

To all whom it may concern:

Be it known that I, OLNEY W. HOWLAND, a citizen of the United States, residing at Lynn, in the county of Essex and State of Massachusetts, have invented a certain new and useful Improvement in Rests for Molding-Machine Flasks, of which the following is a specification.

This invention relates to rests for molding machine flasks and has for its object to provide a new and improved device of this description. In the operation of a rock over molding machine the flask containing the pattern is in one position while the sand 10 is being rammed or packed about the pattern and then the flask is covered and turned over so that this cover becomes the bottom and engages a flask rest. It is desirable that the flask rest be of such form that it 15 automatically adjusts itself as the flask engages it so that the flask may be properly seated and then such flask rest fixed in position to hold the flask in this proper position while the pattern is being withdrawn. One of the objects of the present 20 invention is to provide a flask rest of this description. In the drawings I have illustrated a flask rest of this description.

Fig. 1 is a view showing a side elevation 30 of one form of flask rest;

Fig. 2 is a longitudinal vertical sectional view through the flask rest shown in Fig. 1;

Fig. 3 is a bottom view of the flask rest shown in Fig. 1;

Fig. 4 is an end view of two flask rests showing the flask in position thereon.

Like numerals refer to like parts throughout the several figures.

In the preferred form of using the flask rest I provide two flask rests separated by a space, the flask resting on top of these flask rests as illustrated in Fig. 4.

Each flask rest consists of a flask engaging part 1 which is shown in the form of an enclosing casing open at the bottom and which is preferably provided at the top with the engaging faces 2, the portion 3 between the engaging faces being preferably somewhat depressed (see Fig. 2). Associated with the engaging part is a supporting part 4 which is rigidly held in any desired manner upon a suitable support

such as the rod 5 which fits into an opening in the supporting part 4. The engaging part 1 is movable and preferably elastically connected with the supporting part 4 in some suitable manner, as, for example, by being mounted upon the springs 6 which are interposed between the engaging part and the supporting part 4. I prefer to have projections 7 on the engaging part and projections 8 on the supporting part which project into the springs 6 when coil springs are used so as to prevent the springs from becoming displaced. Connected with the supporting part 1 are two wedges 9 and 10. The wedge 10 is connected to the supporting part by the pin 11 and the inner end thereof rests upon the cross piece 12. The wedge 10 passes between parts 13 on the supporting part which parts also preferably have wedge faces so that when the wedge 10 is forced between these parts the engaging part and supporting part are locked against relative movement. The wedge 9 passes between similar parts 14 at the other end of the rest. The wedge 9 is mounted so that it may be moved longitudinally to engage the faces of the parts 14. This result may be secured in any desired manner as by mounting it upon a cam 15 connected with a shaft 16 which is mounted on the engaging part and which is provided with a handle 17 by means of which the cam may be rotated. The wedge 14 is provided with an enlarged opening 15^a for this cam. I prefer to provide the engaging part with the engaging faces 18 which are engaged by the parts 13 and 14 so as to more securely lock the engaging and supporting parts together. I prefer to provide the engaging part with a stop 19 and the shaft 16 with a stop 20 which engage so as to stop the movement of the cam when the wedges have been sufficiently moved to connect the engaging part 1 with the holding part 4. The inner end of the wedge 9 rests upon a removable cross piece 21 attached to the engaging part in any desired manner as by the screws 22. I have described in detail a particular construction embodying the invention, but it is, of course, evident that the parts may be varied without departing from the spirit

of the invention as embodied in the claims hereto attached, and I, therefore, do not limit myself to the particular construction shown.

5 The use and operation of my invention are as follows:—

When it is desired to rest the flask on the flask rest the parts are in such position that the engaging part 1 is free to move 10 with relation to the supporting part 4, the wedges 9 and 10 being disengaged from the supporting part to permit this. When the flask is then placed upon the flask rest or a plurality of them as illustrated in Fig. 4, 15 the engaging part 1 of the flask rest is then free to move to properly adjust itself so that the flask will be properly seated upon it, the spring 6 permitting this. When the flask has been properly seated the cam 15 20 is moved by moving the handle 17, so as to force the wedge 9 in between the parts 14. As this wedge engages the parts 14 it, as it were, draws the engaging part forward so as to move the wedge 10 into engagement 25 with the parts 13. The handle 17, and the cam 15 therefore act to bring both wedges into operation. As these wedges are pressed against the faces of the parts 13 and 14 they bind or clamp the engaging part to 30 the supporting part so as to prevent any further relative movement between them, thus thereby rigidly clamping them together. The flask is now rigidly held in its adjusted position so that the separation of 35 the pattern from the sand may be properly accomplished. After this has been done, the handle 17 may be moved back to its original position as shown in Fig. 3 so as to bring the parts of the rest into their initial position so that the rest may again be used.

I claim:

1. A flask rest comprising an engaging part for engaging the flask, a supporting part upon which said engaging part is movably mounted, a wedge connected with one of said parts, opposed substantially vertical engaging faces on the other part between which the wedge is received, and means for 45 moving the wedge and the part having the engaging faces relatively longitudinally to bring them into engagement to clamp the engaging part and supporting part together.

55 2. A flask rest comprising an engaging part for engaging the flask, a supporting part upon which said engaging part is movably mounted, separated parts on the supporting part, a wedge adapted to be projected between said separated parts, a shaft connected with the engaging part, a cam on said shaft and engaging said wedge, and means for rotating said cam so as to move the wedge into contact with said separated 60 parts on the supporting part.

3. A flask rest comprising an engaging part for engaging the flask, a supporting part upon which said engaging part is movably mounted, separated parts on the supporting part, a wedge connected with said engaging part and adapted to be projected between said separated parts, and a second wedge at the other end of said engaging part, separated parts on the supporting part between which said second wedge projects, and means for moving said wedges so as to cause them to engage the engaging faces of the separated parts on the supporting part so as to clamp the engaging part and supporting part together. 80

4. A flask rest comprising an engaging part for engaging the flask, a supporting part upon which said engaging part is movably mounted, a spring interposed between said engaging part and supporting part, separated parts on the supporting part, a wedge connected with said engaging part and adapted to be projected between said separated parts, a second wedge at the other end of said engaging part, separated parts on the supporting part between which said second wedge projects, a cam engaging said second wedge, a shaft to which said cam is connected, said shaft mounted upon said engaging part and free to move with relation 90 thereto whereby when the shaft and cam are rotated both wedges are brought into their operative positions to clamp the engaging part and supporting part together. 95

5. A flask rest comprising an engaging part for engaging the flask, a supporting part upon which said engaging part is movably mounted, two separated wedges connected with said engaging part, engaging faces on the supporting part adapted to be 100 engaged by said wedges, and means for forcing the two wedges toward each other to engage said faces.

6. A flask rest comprising an engaging part for engaging the flask, a supporting part upon which said engaging part is movably mounted, a wedge mounted on the engaging part, and means connected with the supporting part for engaging said wedge 110 when it is in its operative position so as to hold it and the flask engaging part in fixed relation with the supporting part. 115

7. A flask rest comprising an engaging part for engaging the flask, a supporting part upon which said engaging part is movably mounted, a wedge connected with said engaging part and in longitudinal alignment with said supporting part, and actuating mechanism for moving said wedge so as to cause it to engage the supporting part 120 and hold the flask engaging part and supporting part in fixed relation. 125

8. A flask rest comprising a substantially horizontally extending engaging part for engaging the flask, a supporting part upon 130

which said engaging part is elastically supported at separated points, a wedge movably mounted on the engaging part, said supporting part being provided with opposed faces and means for moving the wedge between said opposed faces to clamp the engaging part to the supporting part.

In testimony whereof, I affix my signature in the presence of two witnesses this 28th day of June, 1918.

OLNEY W. HOWLAND.
